HANDLE FOR DISHES.

No. 16,060.

Fig. 1.

Patented Apr. 28, 1885.

Fig. 2.

UNITED STATES PATENT OFFICE.

CHARLES EDWARD HAVILAND, OF LIMOGES, FRANCE.

DESIGN FOR A HANDLE FOR DISHES.

SPECIFICATION forming part of Design No. 16,060, dated April 28, 1885.

Application filed February 3, 1885. Term of patent 14 years.

To all whom it may concern:

Be it known that I, CHARLES EDWARD HAVILAND, a citizen of the United States, residing at Limoges, Republic of France, have 5 invented and produced a certain new and original Design for Handles for Dishes, fully described and represented in the following specification and the accompanying drawings, forming a part of the same.

10 This design is illustrated by two perspective views, one, Figure 1, representing a covered dish as viewed from the side, and Fig. 2 the same dish as viewed from the end.

15 This design consists in the shape of the handles applied to dishes.

The handle, as shown, is composed of two scrolls, one represented as laid upon the other, the whole being bent so as to form an arch-like figure. The ends 1 of the major or exterior scroll, 5, are curved or rolled outwardly 20 and projected laterally, and the ends 2 of the interior or minor scroll, 6, are curved or rolled inwardly and projected laterally. The two scrolls are also shown as bound together by a central band, 7, and the exterior one is beautified by a scale-like ornamentation, 8.

25 The essential characteristic feature of the design is the scroll-like configuration of the handle.

30 This design, though shown as embodied in a covered dish, is applicable to the covers or bodies of the various dishes of a table-service

where handles are required, no matter what the shapes may be.

It is to be understood that although a covered vegetable-dish is illustrated, the dishes of a table-course having handles vary in size and depth, some of which are provided with covers, while some are open vessels. Thus a soup-tureen is a covered dish of greater depth 35 than a vegetable-dish, while a butter-dish may be covered or not, and will be of small dimensions and shallow. A tea-cup will be a deep dish of small size, and have a handle arranged vertically with respect to its mouth rather 40 than horizontally. These various arrangements of the handle will be readily understood and come within the scope of this design.

What is claimed is—

1. The design for the handles of dishes, the 50 same consisting of the scroll-like configuration, substantially as shown and described.

2. The design for a covered dish, consisting of a cover and body having handles of scroll-like formation, substantially as shown and described. 55

In testimony whereof I have hereunto set my hand in the presence of two subscribing witnesses.

CH. ED. HAVILAND.
